(57) **CLAIM**

The ornamental design for a container with surface indicia, as shown and described.

DESCRIPTION

FIG. 1 is a front perspective view of the first embodiment of the container with surface indicia, embodying our new design;

FIG. 2 is a front view thereof;

FIG. 3 is a first side view thereof;

FIG. 4 is a back view thereof;

FIG. 5 is a second side view thereof;

FIG. 6 is a top view side thereof; and

FIG. 7 is a bottom view thereof;

FIG. 8 is a front perspective view of the second embodiment of the container with surface indicia, embodying an embodiment of our new design;

FIG. 9 is a front view thereof;

FIG. 10 is a first side view thereof;

FIG. 11 is a back view thereof;

FIG. 12 is a second side view thereof;

FIG. 13 is a top view thereof; and

FIG. 14 is a bottom view thereof;

FIG. 15 is a front perspective view of the third embodiment of the container with surface indicia, embodying an embodiment of our new design;

FIG. 16 is a front view thereof;

FIG. 17 is a first side view thereof;

FIG. 18 is a back view thereof;

FIG. 19 is a second side view thereof;

FIG. 20 is a top view thereof; and,

FIG. 21 is a bottom view thereof.

The broken lines shown in the drawings are for illustrative purposes only and form no part of the claimed design.
